PRESSURE EXERTING DEVICE

Application filed October 8, 1927. Serial No. 224,918.

This invention relates, generally, to means for setting-up and tightening forms used in pouring concrete structures; and the invention has reference, more particularly, to a 5 novel construction of a device which may itself be used as a clamp means upon tie-rods and similar elements employed to bind the walls of concrete forms in operative assembled condition, or which may be used as a 10 tightening or setting-up tool for pressing home clamp-collars upon the tie-rods of concrete form structures.

This invention has for its principal object to provide a novel and very efficient device 15 for the purposes above indicated, which is reduced to very few parts of simple construction and arrangement; which in operation is self-locking on a tie-rod while adapted to exert tightening and holding upon a form 20 wall, or to exert tightening pressure upon a clamp-collar preparatory to tightening set-screws by which the latter is finally locked on the tie-rod in holding relation to a form wall.

Other objects of this invention, not at this 25 time more particularly enumerated, will be clearly understood from the following detailed description of the same.

The invention is clearly illustrated in the 30 accompanying drawings, in which:—

Figure 1 is a transverse section through a concrete form showing a tie-rod extending therethrough to bind the side walls of the form in assembled relation, said tie-rod having a clamp-collar thereon, and the novel 35 tightening device embodying my present invention being shown in side elevation in operative relation to the tie-rod and clamp-collar and as employed to tightly set up the 40 latter preparatory to finally locking the same to the tie-rod; Figure 2 is a similar view, with the clamp-collar and tightening device shown in vertical section; and Figure 45 3 is a top-side elevation of clamp-collar and tightening device, as disposed in Figure 1.

Figure 4 is a view similar to that shown in Figure 1, but illustrating the novel tightening device as above used to lock up and clamp the form walls in place.

Figure 5 is a view similar to that shown

in Figure 1 but illustrating a simplified construction of my novel tightening device which embodies however the essential principles of the instant invention.

Referring first to Figures 1 to 3 inclusive 55 of the drawings, the reference character 10 indicates the side walls of a concrete form and 11 a tie-rod extending therethrough to secure the same in the desired assembled relation. One end of the tie-rod may be provided with a head 12, or any other suitable form of stop for engaging the tie-rod with a wall 10 at one side of the form. The opposite end 11' of the tie-rod extends in outward projection through and upon the exterior 65 face of the wall 10 at the other side of the form. Slidably disposed on the free projecting end portion 11' of said tie-rod is a clamp-collar 13, preferably provided at its inner end with a flange 14 to furnish a broad bearing for engagement with the adjacent side wall 10 of the form. Said clamp-collar is preferably provided with set screws 15 threaded into and through opposite sides 70 thereof. The said clamp-collar 13, in practice, is forced tightly home on the tie-rod to abut the exterior face of the adjacent wall 75 of the concrete form, whereupon the set screws 15 are turned into biting engagement with the tie-rod to hold the clamp-collar in 80 such operative holding relation to said form wall. It is desirable before locking the clamp-collar on the tie-rod to be assured that the same is firmly and tightly pressed into desired operative holding relation to the 85 form wall. In order to thrust home the clamp-collar into such desired relation to the form I have provided the device of the instant invention by means of which a very considerable thrusting pressure can be exercised on the collar both to drive the same home and to hold the same in the desired tightened relation to the formed wall preparatory to locking the same on the tie-rod 90 by means of the set screws 15. The novel 95 device, adapted to so function, comprises a gripping plate 16 having through its body an opening 17 through which the end 11' of the tie-rod may be extended. Said opening 17 of the gripping plate is slightly larger 100

in diameter than the diameter of the tie-rod and when disposed on the latter and canted thereon the margins of the opening 17 respectively at the upper and lower edges there-
5 of indicated by the reference character 18, will provide biting edges for gripping the tie-rod when the device is being used. Pivot-
ally connected between ears 19 which are integrally formed with one end of said grip-
10 ping plate 16, and by means of the pivot pin or bolt 20 is a forwardly extending link 21 which terminates at its free end in a slide sleeve 22 through which the tie-rod 11 ex-
tends so that said sleeve can slide thereon.
15 Connected with the sides of the sleeve so as to project laterally therefrom in opposite directions are journal studs 23. The refer-
ence character 24 indicates a backing plate provided with an opening 25 through which
20 the tie-rod 11 may extend. Said backing plate is preferably made of malleable iron and springing from its rear face and prefer-
ably forming an integral part thereof are pairs of yoke fingers 26, the members of
25 which may be bent around the journal studs 23 so as to pivotally connect said backing plate with the sleeve for turning movement on the horizontal transverse axes of said jour-
nal studs 23. Affixed to the front face of said
30 backing plate 24 is a facing of frictional mate-
rial 27. This frictional material may consist of leather, rubber, asbestos, fabric, wood, ap-
parently soft metal, or any other desirable material calculated to set up a frictional re-
35 sistance to slip as to any metal material bearing against the same. Cooperating with said backing plate and the parts serving to anchor the same in position in the manner subse-
quently to be described, is a vertically mov-
40 able wedge member 28, this wedge member 28 is provided with an opening 29 through its rear side whereby the wedge may straddle the tie-rod 11 and yet be vertically movable relative thereto. The wedge may be subject
45 to considerable variation as to its detail form so long as the characteristic converging front and rear faces of the same are provided.

In making use of the device of this invention for setting up and tightening a clamp 50 collar arranged upon a tie-rod and movable thereon against a form wall to hold the latter, the wedge member 28 is engaged over the tie-rod rearwardly of the clamp collar and the backing plate with its anchoring elements
55 are next engaged over the tie-rod behind and in contact with the wedge member, the latter being under such conditions in an initial raised position. Owing to the pivotal con-
nection of the backing plates 24 with its
60 anchoring means the same will readily conform itself to the angle of the wedge member and in such a manner as to give a broad bearing surface against which the wedge member may thrust or gain purchase. In
65 the initial arrangement of the device on the

tie-rod the wedge is raised and the backing plate is moved up against the rear face of the same and gripping plate 16 canted rearward so as to bring the gripping edges 18 of its opening in contact with the tie-rod, all in the manner shown in Figure 2 of the drawings. With the parts in the initial position just above described and with the set screws 15 of the clamp-collar loosened so that said clamp-collar may slide on the tie-rod, the de-
vice is ready for operation. The manner of actuating the device consists merely in driv-
ing down the wedge 28. The effect of down-
ward movement of the wedge under suitably applied downward driving force is to cause
70 the same to thrust back against the backing plate 24, and this tendency of the backing plate 24 to move rearward is in turn trans-
mitted to the link 21 whereby a rearward thrusting pressure is exerted on the upper end of the canted gripping plate 26 so that the biting edges 18 of the opening thereof are caused to strongly grip the tie-rod so as to hold the gripping plate immovable thereon and thus in turn hold the backing plate and interconnecting link against any rearward yielding movement. The backing plate being thus held against rearward yielding at once provides the necessary purchase against which the wedge 28 may act as it is driven
75 downward to the end that the thrust of the wedge is exerted entirely upon the slidable collar 13 and so that the latter is forced forwardly into tight holding relation to the adjacent form wall 10. Incidental to the operation it would be obvious that the tie-rod would also be drawn in such a manner as to cause its opposite headed end 12 to be like-
wise tightly engaged with the opposite form wall 10. After the clamp collar has thus
80 been pressed home the set screws 15 may be tightened so as to lock the clamp bars im-
movably upon the tie-rod and maintain in proper holding engagement to the form wall.
85 After the collar has thus been locked the tightening device may be removed from the tie-rod and used over again for a repetition
90 of the operation in connection with another tie-rod and its clamp collar. To remove the tightening device all that is necessary to do is to exert an outwardly swinging pressure on the lower end of the gripping plate 16 where-
95 by the same is quickly and easily released from its gripping relation to the tie-rod so that both it and the sleeve 22 and backing plate 24 may be slid off the end of the tie-rod. In order to prevent the wedge member 28 against receding from its downwardly driven wedging relation to the clamp collar, the frictional facing 27 above described in pro-
100 vided on the backing plate 24, the same offer-
ing sufficient friction to retain the wedge against upwardly yielding movement.
105 Owing to the novel character involved in the construction and arrangement of parts
110

115 120 125 130

making up the tightening device of this invention it is possible to use the same per se as means for directly engaging and locking relation. Such use is illustrated in Figure 4 of the drawings and it will be obvious from an inspection of said figure that with the clamp collar removed the wedge member 28 may exercise its thrust directly against the adjacent form wall, the holding of the backing plate 24 against rearward yielding is attained by the action of the gripping plate 16 in the same manner as already above described so that as the wedge is driven downward relative to the unyielding backing plate 10 it will thrust tightly into place and will hold the adjacent form wall in desired assembled position. The tightening device when used alone in the manner just described is self locking and will continue to tightly bind the form wall in position until such time as it may be released by disengaging its gripping plate 16 from operative gripping relation to the end of the tie-rod 11, or by knocking out the wedge.

Referring to Figure 5 of the drawings, I have shown therein a form of my instant invention in which the parts making up the same have been reduced to a minimum, while yet retaining the elements necessary to its proper functioning by the general mode of operation already above indicated. In this modified simple form of the invention I provide a gripping plate 30 having an opening 31 in its body through which the end 11' of a tie-rod may extend and said opening providing at its upper and lower edges 32 portions adapted to grip the tie-rod when the gripping plate is canted or tilted to operative position. Extending from the upper end of said gripping plate and preferably integral therewith is a forwardly projecting extension or arm 33. Adapted to cooperate with the gripping plate 30 thus constructed is a wedge member 34. In the use of the device of the described simplified form the gripping plate 30 is engaged upon the end of the tie-rod 11' and canted thereon by swinging backwardly its upper end and the same is positioned in an outwardly spaced relation to the adjacent form wall 10 so that the wedge member 34 may be interposed between said form wall 10 and the extremity of the arm 33 of said gripping plate. It will be readily understood that when the parts are in such position that the wedge member 34 may be driven downwardly and as its downward movement is initiated it will tend to thrust rearwardly upon the end of the arm 33 in engagement with its rear face whereby rearward thrusting pressure is exerted on the upper end of the gripping plate 30 which will not only hold the same in canted position but which will cause the gripping edges 32 of its opening 31 to bind upon the tie-rod so as to firmly and unyieldably secure the gripping

plate thereto. As a consequence of this action as the wedge members continue to be driven down the arm 33 serves to give purchase thereto in a forward thrusting action thereof upon and against the adjacent form wall 10, all of which will be understood from inspection of Figure 5. As shown in Figure 5 the device in this simplified form may be used as a self locking form clamping and tightening device, but it will also be obvious that the device in this simplified form may also be used, should it be so desired, for setting up clamp collars in the manner substantially the same as that described above.

The gripping plate, either in the form shown in Figures 1 to 4 or in the form shown in Figure 5, is preferably made of hardened steel. Attention is called, however, to my copending application Serial No. 192,970, filed May 20, 1927, in which a gripping element functioning relative to a tie-rod in a manner similar to that indicated in the instant case is shown and in which provision is made for removably mounting a show plate in connection with the gripping member. An arrangement of this kind may be employed in connection with the construction of the instant invention if desired.

It will be obvious that the novel device above described is not limited for use in setting up concrete forms only, but that the same may be employed in connection with any other character of structure, or for any operation wherein it is desired to forcibly move a sliding member on a rod, shaft or other means in connection with which it may be mounted.

I am aware that some changes may be made in the above described constructions and any widely different embodiments of this invention could be made without departing from the scope thereof; it is intended, therefore, that all matter contained in the above description and shown in the accompanying drawings shall be interpreted as illustrative and not in a limiting sense.

Having thus described my invention, I claim:

1. A pressure exerting device of the kind described engageable with tie-rods of concrete forms or other structures, comprising a gripping element having an opening through which a tie-rod may extend, to dispose said element transversely of said tie-rod, said gripping element being tiltable on said tie-rod in direction of the longitudinal axis of the latter to bring edges of its opening into gripping engagement with the tie-rod, a wedge member, and a forward angularly extending means connected with one end portion of said gripping element engageable by said wedge member and operative under back-pressure thereof to tilt and hold said element in gripping relation to said tie-rod.

2. A pressure exerting device of the kind

described engageable with the tie-rods of concrete forms or other structures, comprising a gripping element tiltable relative to a tie-rod, said element having means to grip the tie-rod when tilted, a tilting-link pivoted by one end to an end of said gripping element and having its opposite end slidably related to a tie-rod, a backing-plate pivotally connected with said tilting-link, and a wedge-member backed by said backing-plate and adapted to thrust rearwardly against the same to actuate said tilting-link and through it said gripping element while exerting forward thrusting pressure relative to a form structure or the like.

5. In a pressure exerting device as defined in claim 2 in which said backing-plate is provided with a facing of frictional material engageable by the wedge member.

20. 4. A pressure exerting device of the kind described engageable with the tie-rods of concrete forms or other structures, comprising a gripping element having an opening through which a tie-rod may extend, said gripping element being tiltable relative to a tie-rod to bring edges of its opening into gripping engagement with said rod, a tilting-link pivotally connected with an end portion of said gripping element, said tilting-link having a sleeve at its free end slidable on said tie-rod, a backing-plate having an opening through which said tie-rod may extend, means to pivotally connect said backing-plate with said sleeve, and a wedge member backed by said backing-plate.

25. 5. A pressure exerting device of the kind described engageable with the tie-rods of concrete forms or other structures, comprising a gripping element having an opening through which a tie-rod may extend, said gripping element being tiltable relative to a tie-rod to bring edges of its opening into gripping engagement with said rod, a tilting link pivotally connected with an end portion of said gripping element, said tilting-link having a sleeve at its free end slid-
30. able on said tie-rod, a backing-plate having an opening through which the tie-rod may ex-
35. tend, means to pivotally connect said back-
40. ing-plate with said sleeve, a wedge member backed by said backing-plate, and said back-
45. ing-plate having a facing of frictional ma-
50. terial engageable by said wedge-member.

In testimony that I claim the invention set forth above I have hereunto set my hand this 7th day of October, 1927.

SAMUEL S. COLT.
